UNITED STATES PATENT OFFICE.

JAMES N. STEVENSON, OF SALVISA, KENTUCKY.

PLOW.

SPECIFICATION forming part of Letters Patent No. 308,006, dated November 11, 1884.

Application filed July 29, 1884. (No model.)

To all whom it may concern:

Be it known that I, JAMES N. STEVENSON, of Salvisa, in the county of Mercer and State of Kentucky, have invented a new and useful Improvement in Plows, of which the following is a full, clear, and exact description.

My improved plow, although suitable for use on level ground and as a cultivator after planting, is more particularly intended to be used as a side-hill corn-planter; and its main object or great advantage over the ordinary "double shaper" and other planters is its adaptability to be worked on steep hillsides and in rocky or trashy land.

15 The invention consists in a supplementary plow-frame or beam-extension adjustable to either side of the main plow-beam, and in a special construction of the same to provide for such adjustment, substantially as herein-
20 after described.

Reference is to be had to the accompanying drawings, forming part of this specification, in which similar letters of reference indicate corresponding parts in both the figures.

25 Figure 1 represents a side elevation of a corn-planting plow embodying my invention, and Fig. 2 a plan view of the same.

A indicates the main plow-beam; B, its share; C, the foot or standard, and D the col-
30 ter.

E are the handles of the plow, and F the corn hopper or dropper, provided, as usual, with a slide which is controlled by any appropriate hand mechanism—as, for instance, by a hand-lever, b, having its fulcrum at c, and connected by rod or chain d e with an arm, s, on a rock-shaft, f, and with a spring, g, said rock-shaft having an arm, h, that is connected by means of a rod, i, with the slide in the corn hopper or dropper F, and the hand-lever b serving to open the slide to drop or de-
40 posit the corn, and the spring g to close it.

45 A' is the supplementary plow-beam or beam-extension provided with a shoe, B', a foot or standard, C', and a colter, D'. This plow-beam extension, with its described attach-
50 ments, is arranged to lie to one side of the rear portion of the main beam A, as shown

by full lines in Figs. 1 and 2, or to either side of the main beam, as shown by full and dotted lines in Fig. 2, to do the hillside or special work required of the plow and planter. For this purpose the beam-extension A' is fitted to revolve or turn horizontally from the back end of the main beam to opposite sides of the latter, and to this end the connecting parts or ends of said beams A A' are slotted horizontally, and connected by a link, G, and pivots k l with each other, as by a hinged joint. When the beam-extension A' is swung to a position in line with the main beam or beam portion A, and in rear thereof, the share B' and colter D' face in a reverse direction to the share B and colter D of the beam A; but when said beam-extension A' is swung or folded over horizontally on either side of the main beam A, as shown by full and dotted lines in Fig. 2, then the share B' and colter D' face in the same direction, but to one side of the advance share B and colter D, and when the beam-extension A' is thus adjusted it is held in lock by a tooth, m, on the free end of it engaging with a latch, n, on either side of the main beam A, or by any other suitable means.

75 A very important advantage of this combined plow and planter is that the horizontally-swinging beam-extension A', with its attached share B', always provides for said share, which operates as a covering-shovel, 80 being on the upper side of the hill when at work.

Having thus described my invention, what I claim as new, and desire to secure by Letters Patent, is—

85 1. The combination, with the beam A of the plow and its share B, of the rear beam-extension, A', with its attached share B', adjustable to opposite sides of the main beam A, substantially as specified.

90 2. The combination, with the beam A of the plow and its share B, of the rear beam-extension, A', with its attached share B', the link G, connecting said beam-extension by pivots k l with the rear end of the main beam A, and a catch for holding said beam-extension

in position when swung horizontally to either side of the main beam A, essentially as described.

3. In a combined plow and planter, the combination of the main beam A, with its attached share B and colter D, the hopper or dropper F, and mechanism for controlling the same, and the horizontally-swinging beam-extension A', with its attached share B', colter

D', and pivoted link-connection G, adjustable to or reversible from the rear end of the main beam A to opposite sides thereof, substantially as shown and described.

JAMES N. STEVENSON.
